UNITED STATES PATENT OFFICE.

LOUIS P. SAVAGE, OF LAPORTE, INDIANA.

VALVE MECHANISM FOR INTERNAL-COMBUSTION MOTORS.

1,213,027.

Specification of Letters Patent. Patented Jan. 16, 1917.

Application filed February 7, 1916. Serial No. 76,732.

To all whom it may concern:

Be it known that I, LOUIS P. SAVAGE, a citizen of the United States, residing at Laporte, in the county of Laporte and State 5 of Indiana, have invented new and useful Improvements in Valve Mechanisms for Internal-Combustion Motors, of which the following is a specification.

This invention relates to valve mechanism 10 for internal combustion motors, and one of its objects is to provide a valve mechanism which is arranged externally of the engine cylinder so as to render the valves readily accessible for renewal or repairs, and so as 15 to reduce the amount of carbonization within the firing chamber or combustion space, due to the presence of an increased quantity of oil employed in the lubrication of internally arranged valve devices.

20 A further object of the invention is to provide reciprocating slide valves which are operated in timed accord by eccentrics from the engine shaft to control the intake and exhaust, and each of which consists of a 25 pair of telescopic members, arranged one within the other, and having ports movable into and out of coincidence for valve opening and closing actions, whereby a simple, reliable, positive and efficient type of valve 30 will be produced.

A still further object of the invention is to provide a valve of the character described in which the inner valve member also serves as a lubricating device for supplying oil to 35 the working parts of the valve, and which lubricating device may be supplied with oil from the oil circulating system of the engine.

The invention consists of the features of 40 construction, combination and arrangement of parts herein fully described and claimed, reference being had to the accompanying drawings in which:—

Figure 1 is a side view of a cylinder of 45 an internal combustion engine embodying my invention, showing the intake and exhaust valve devices and the means for operating the same from the engine shaft. Figs. 2 and 3 are vertical transverse sections through the engine cylinder taken on the line of the valves and showing the valve devices in different positions. Fig. 4 is a horizontal transverse section on the line 5—5 of Fig. 2. Figs. 5 and 6 are detail 50 views of the members of one of the valve devices separated from each other.

Referring to the drawings, 1 designates an engine cylinder, which is provided with intake and exhaust ports 3 and 4 and externally arranged intake and exhaust valve 60 casings 5 and 6, arranged in line with said intake and exhaust ports 3 and 4 and at diametrically opposite sides of the cylinder, the said casings being provided with a primary admission port 7 and a final discharge 65 port 8, arranged in alinement with the ports 3 and 4, for connection with the inlet and exhaust manifolds. As shown in the present instance, the cylinder 1 is closed at its top by a removable head 9, which may be 70 bolted or otherwise detachably secured thereto, which head is provided with lateral extensions 10 and 11 which close the upper ends of the valve casing. The parts described are suitably hollowed to form a 75 water jacketing space 12 surrounding the cylinder body proper and the valve casings to keep the same cool, as will be readily understood.

The valve casings are similar in construction to each other, and each comprises a circular body portion 13 which is integral with the cylinder, and joined to the body of the cylinder by a narrow intervening neck portion, which is formed to provide a flat 80 seat face 15 and grooved guideways 16 and 17.

85 Arranged within the respective casings are intake and exhaust valves 18 and 19 which are similar in construction to each other, so that a description of one will suffice for both, said valves being composed of parts which are operated from the crank shaft 20 of the engine as hereinafter fully described. Each valve comprises an outer 90 tubular member 21 provided with diametrically arranged ports or passages 22 for co-operation with the ports 3 and 7, and an inner hollow member 24 provided with a port or passage 25. The valve member 21, 100 which forms a casing for the valve member 24, and which valve members slide or reciprocate in opposite directions in unison, is provided at its inner side with a flattened seat surface 26 to engage the seat 15 and 105 lateral guide flanges 27 to engage the grooved guideways 16 and 17, whereby the outer valve member is fitted to slide in a directly rectilinear path. Upon the flattened seat face of this valve member are recesses 110 in which are fitted spring packing strips 28 which ride in contact with the

seat face 15 and operate to prevent leakage of motive fluid or oil. The valve members are provided at their lower ends with wrist pins 29, and the valve members of the intake 5 valve device are connected with eccentrics 30 and 31 on the crank shafts by connecting rods 32 and 33, while the wrist pins of the valve members of the exhaust valve device are connected with eccentrics 34 and 35 on 10 the crank shaft by connecting rods 36 and 37, said eccentrics being arranged to properly time the movements of the respective valves and valve members for the intake and exhaust actions at proper periods in the 15 cycle of operation of the engine. The inner valve members of the valve devices form reservoirs for oil or other lubricating fluid, and such reservoirs may be supplied with oil in any preferred manner. In the present 20 instance, each inner valve member is shown as provided with a check valved nipple 39 for connection with a hose pipe or other connection 40 leading from the pump or other part of the oil circulating system 25 of an engine employing force feed lubrication, whereby oil may be supplied through ports 38 therein to the working surfaces of the valves to keep the same thoroughly lubricated.

30 In the operation of the engine, it will be understood from the foregoing description that the intake and exhaust valves will be operated in timed accord by eccentrics, as will also the members of each valve, to bring 35 the ports in coincidence at proper intervals in the cycle of operation of the engine for the admission of the fuel charge and subsequent discharge of the spent gases. It will be seen that in the operation of each valve 40 the members thereof in moving in opposite directions will shift their coöperating ports toward or away from each other, and that when the ports of the valve members are in register they will also coincide with the 45 ports of the valve casing and cylinder for the admission of the charge or the exhaust of the spent gases, as the case may be. In the movement of the elements of each valve, oil will be forced between the surfaces of 50 the valve members and under the force feed action of the lubricating system, whereby through the movement of the parts of the valve the oil will be distributed to the working surfaces of the valve, whereby the same 55 will be kept properly lubricated.

It will be observed that the described arrangement of the valve mechanism provides for the ready application and removal of the valves in assemblage, disassemblage, 60 cleaning and repairs, and for the arrangement of all parts of the valve upon the exterior of the cylinder, thus preventing the

passage of an undue amount of oil to the interior of the cylinder and the consequent burning of the same and increased carbonization resulting therefrom. Hence carbonization will be retarded, with increased efficiency of the engine, while, as the valves are of a type and so arranged to protect the same from carbon deposit, no loss of compression from imperfect seating of the valves due to the presence of carbon will occur and no regrinding of valves at frequent intervals will be required. Furthermore, as there will be less tendency to leakage of oil or fuel, greater power will be obtained while the engine cylinder is maintained in a more cleanly condition, and liability of spark trouble will also be diminished. The advantage of my improved 75 valve mechanism will therefore be readily understood and appreciated without a further or extended description.

I claim:

1. In a valve mechanism for internal 85 combustion motors, the combination with a cylinder having a port therein, of a valve for coöperation with said port, said valve comprising sliding, telescopically connected parts having coöperating ports, the inner 90 valve part consisting of a hollow body forming a reservoir, and means for supplying oil through said reservoir to the working surfaces of the valve parts.

2. In a valve mechanism for internal 95 combustion motors, a cylinder having a port therein, a casing provided with a coöperating port, telescopically connected valve members operating in said cylinder, one of said valve members forming an oil reservoir, means for simultaneously reciprocating said valve parts in opposite directions, and means for supplying oil under pressure to said oil reservoir and from thence to the surfaces of the valve members.

3. In a valve mechanism for internal combustion motors, a cylinder having a port therein, a casing upon the exterior of said cylinder, a valve in said casing composed of sliding, telescopically connected 110 parts having coöperating ports, the inner valve part comprising a hollow body forming an oil reservoir having an oil discharge port therein, means for supplying oil to said reservoir, and means for simultaneously reciprocating the valve members in opposite directions in unison.

In testimony whereof I affix my signature in presence of two witnesses.

LOUIS P. SAVAGE
